[57] CLAIM

The ornamental design for a jewelry display rack, as shown and described.

DESCRIPTION

FIG. 1 is a perspective view of a jewelry display rack showing my new design;

FIG. 2 is an enlarged detailed perspective view of the encircled area in FIG. 1;

FIG. 3 is a reduced scale elevational view, shown broken away for convenience of illustration, the other sides being identical thereto;

FIG. 4 is a top plan view thereof; and

FIG. 5 is a bottom plan view thereof.

FIG. 1

FIG. 2

FIG. 3

FIG. 4

FIG. 5
